FALSE EYELASH HOLDER

David Seidler, 69-10 108th St.,
Forest Hills, N.Y. 11375

Filed June 1, 1970, Ser. No. 23,224

Term of patent 14 years

Int. Cl. D3—99

U.S. Cl. D87—1

FIG. 1 is a top plan view of a false eyelash holder embodying my new design;

FIG. 2 is an elevational view thereof;

FIG. 3 is an exploded elevational view thereof; and

FIG. 4 is a top plan view looking in the directions of the arrows 4-4 in FIG. 3.

I claim:

The ornamental design for a false eyelash holder, as shown.
